UNITED STATES PATENT OFFICE.

SAMUEL J. PETERSON, OF VALDOSTA, GEORGIA.

PUMPING APPARATUS.

1,089,955.

Specification of Letters Patent. Patented Mar. 10, 1914.

Application filed June 18, 1909; Serial No. 502,980. Renewed August 18, 1913. Serial No. 785,364.

To all whom it may concern:

Be it known that I, SAMUEL J. PETERSON, a citizen of the United States, residing at Valdosta, in the county of Lowndes and 5 State of Georgia, have invented new and useful Improvements in Pumping Apparatus, of which the following is a specification.

This invention relates to new and useful 10 improvements in pumping apparatuses and has more particular reference to an apparatus intended especially for use in fighting fires; although equally advantageous in other cases where a pump may be desirable for the 15 ordinary or usual purposes.

The invention proposes to combine with a water pump, an air pump which may be driven from the same prime mover as the water pump and which assists the mechanical action of the latter in discharging the water, causing the stream to have an increased speed and force.

It is a well known fact that a great deal 20 of the power employed in conducting water is expended in overcoming friction which is chiefly incident to the non-elastic nature of water and the present invention proposes to provide for the utilization of this surplusage of power which ordinarily is wasted 25 in overcoming friction, by maintaining and providing for the maintenance of an expansible, elastic water forcing agent in connection with the water pump. The water pump is thus employed to complete 30 one stage of the water forcing operation while the body of elastic fluid under compression is employed to complete the final stage of the water forcing operation. In 35 this manner the capacity of the machine as an entirety is materially increased, since the body of air which completes the final stage of the water forcing operation, operates with less friction and less waste of power than would a pump under the same 40 circumstances.

In the accompanying drawings I have illustrated a preferred and advantageous embodiment of the invention.

In the said drawings: Figure 1 is a side 50 elevation of an apparatus constructed in accordance with the present invention. Fig. 2 is a top plan view thereof, and Fig. 3 is a detail plan view of the compressor tanks and water pumps.

55 Similar characters of reference designate

corresponding parts throughout the several views.

As shown in Fig. 1, the apparatus is mounted on a suitable supporting frame 1 and consists essentially of a prime mover, 60 as for example, a steam engine, 2, an air pump, 3, and a water pump, 4. For convenience, the crank shaft 5 of the engine 2, is employed to drive the pump 3. This arrangement is not to be considered as obligatory; however. The pump 3 may be of any approved form and in the embodiment shown, is employed to charge a pair of air compression tanks, 6, into which air flows from the pump 3 through a connection pipe 70 65 7, the latter having a suitable check valve, 8, therein. The crank shaft 5 is also employed to operate the pump 4 and accordingly said shaft has at its ends oppositely extended crank arms to which are connected links, 9, the latter being in turn connected to levers 10. The levers 10 are pivoted intermediate their lengths and at their lower ends are operatively connected to the extended piston rods 11 of the pump 4, the latter being preferably of the well known duplex construction and being surmounted by a water tank 12, provided with an air dome 13. A water discharge pipe, 14, leads from the tank 12, and may be connected to a hose 85 or to a stationary piping system. The pipe 7 connects with one of the tanks 6 and from the other of said tanks a pipe, as 15, leads. The pipe 15 is provided with a suitable check valve, 16, and has a branch 17, which opens into the upper portion of the tank 12 and also a branch, 18, which opens into the discharge pipe 14.

In operation the pump 4 forces water into the tank 12 from whence it is violently discharged by the column of air confined in the dome 13 and also by the action of the air admitted to the pipe 14. The pump 4 is thus allowed to work at its maximum speed 95 in charging the tank 12 with water, the discharge of which from said tank is effected by air, with less waste of power than would be the case if the pump 4 were relied on for this purpose.

The tank 12 has been shown in the drawings smaller in proportion to the size of the pump 4 than it will be in actual practice, the scale of drawings having been adopted for the purpose of convenience of illustration only. It will, therefore, be understood 100 105 110 115

2
that air alone may be employed to force water from the tank 12 in the event of the pump 4 becoming deranged or of its action being stopped.

5 It will be understood that the machine may be constructed for use in connection with stationary systems or it may be of portable nature.

Having fully described my invention, I
10 claim:

In a pumping apparatus, the combination
of a water pump; a receiving tank in com-
munication therewith and having an air
15 dome; a water-discharge pipe leading from
said tank; an air pump structurally inde-
pendent of the water pump; a compressed
air reservoir, a pipe connecting said reser-
voir and said air pump; a pipe connecting

said reservoir and dome for supplying com-
pressed air from the former to the latter, 20
whereby the water contained in said tank
will be forced by the compressed air through
said discharge pipe; valves in said connect-
ing pipes; and a branch pipe leading from
the second-named connecting pipe to the 25
discharge pipe for supplying compressed air
to said discharge pipe to facilitate the dis-
charge of water from said tank.

In testimony whereof I have hereunto set
my hand in presence of two subscribing 30
witnesses.

SAMUEL J. PETERSON.
